CLAIM

The ornamental design for a cheese slicer, as shown and described.

DESCRIPTION

FIG. 1 is a perspective view of a cheese slicer showing our new design, the broken lines are for illustrative purposes only and form no part of the claimed design;

FIG. 2 is an end view thereof;

FIG. 3 is an opposite end view thereof;

FIG. 4 is a side view thereof;

FIG. 5 is an opposite side view thereof;

FIG. 6 is a front view thereof; and,

FIG. 7 is a rear view thereof.
